ROLLING MILL

Hans L. Schreck, Easton, Pa., assignor to Treadwell Engineering Company, Easton, Pa., a corporation of Pennsylvania

Application January 19, 1932, Serial No. 587,574

4 Claims. (Cl. 80—56)

The present invention relates to rolling mills and particularly to mills of the type in which it is necessary to very accurately adjust the relative positions of adjacent rollers to cause them to define, between them, a pass suitable for the rolling of plates, strips, or sheets which, in finished condition, must conform exactly or very nearly to predetermined specifications with respect to size, particularly with respect to thickness.

It is sometimes necessary to effect an exceedingly fine adjustment of at least one of the rolls of a mill to secure a pass of the desired vertical dimension, and occasionally it is necessary to adjust one end, or both ends, of one of the rolls upwardly or downwardly through the one fivethousandth part of an inch to secure perfect parallelism of the roll surfaces, and a product with exactly parallel faces. Particularly where sheets are to be rolled, the mill should have the capacity for very fine adjustment of the rolls, and the present invention may therefore be said to be particularly useful in connection with sheet rolling mills, particularly mills for cold rolling.

Various expedients have been resorted to heretofore by manufacturers and operators of rolling mills for obtaining very fine relative adjustments of the mill rolls, such, for instance, as the provision of double worm gear reduction mechanisms between the electric motor which is usually employed to effect the adjustment and the threaded rod or screw which is operatively connected to the roll bearing blocks and by means of which screw movement of the bearing and roll is effected. A double worm gear reduction mechanism, however, necessarily involves a considerable amount of lost motion between the motor and the screw due to the presence of numerous bearings and play or back-lash between the intermeshing teeth of the gearing. In an appliance of this kind also, it is not possible to accurately indicate to the operator very small angles of rotation of the adjusting screw or screws due to the fact that, for a fine adjustment of the screw, its motion is almost imperceptible and to the fact that the position of the motor armature which drives the mechanism, or the angle through which the armature rotates in effecting the adjustment, do not truly indicate the extent of the adjustment by reason of the lost motion inherent in the reduction gearing.

The operators of mills which are not provided with mechanisms of the type just briefly described sometimes attempt to secure very fine adjustments of the rolls by rotating the nuts hav-

ing threaded engagement with the roll adjusting screws through very small angles by blows of a hammer or sledge. This method naturally is crude and unsatisfactory, being injurious to the mechanism and never very accurate. In accordance with the present invention, a mechanism is provided whereby very fine adjustments of the relative positions of the rolls may be obtained quickly and accurately and also without the abandonment of the electric motor as a source of power for effecting the adjustment so that the operator is enabled to easily effect any necessary adjustment within a few seconds.

The invention contemplates the provision in a rolling mill of a sleeve to encircle or envelop each of the threaded rods or screws by which roll adjustment is ordinarily secured, this sleeve being interiorly threaded so as to have threaded engagement with the associated screw and being also exteriorly threaded so as to have threaded engagement with the aperture in the frame or housing through which both the sleeve and rod project. The exterior and interior threads of the sleeve are of the same hand but differ slightly in pitch. Thus, when the sleeve is rotated through one revolution, with the associated screw held against rotation, the net longitudinal movement of the screw connected to the roll bearing is equal to the difference in pitch between the interior and exterior threads of the sleeve. By properly choosing the relative pitch of the exterior and interior threads of the sleeve, the desired longitudinal movement of the screw for each revolution of the sleeve can be obtained. Furthermore, means is provided whereby either the threaded sleeve or the screw may be rotated at the will of the operator, the second of these members remaining stationary, that is, not rotating, during rotation of the first. This permits the operator to hold the sleeve stationary and rotate the screw if a fast movement or adjustment of the associated roll is desired. A very fast movement of the roll may be obtained by rotating both sleeve and screw at the same time, but such procedure is generally unnecessary.

In adapting the invention to rolling mills which vary in type, function, and details of construction, the invention may be considerably modified in the design and arrangement of its component parts. In the accompanying drawings, one embodiment is disclosed, but it will be appreciated by those skilled in the art that this is set forth by way of example only.

In the drawings:—
Figure 1 is a top plan view of a rolling mill to

which the invention has been applied, one housing plate having been removed; and

Figure 2 is a section on line 2—2 of Figure 1.

A portion of the housing of the mill is indicated at 10 and the neck of the upper roll at 11, this roll neck being rotatably supported in a suitable bearing block assembly generally indicated at 12, which block is vertically movable in the guideway formed by the mutually facing, 10 parallel, vertical surfaces 13 of the housing. It will be understood that the upper roll of the mill is supported at both ends in bearing blocks such as that illustrated and that roll adjusting mechanism shown in Figure 2 is duplicated at the opposite end of the roll.

On its upper surface, the bearing block 12 is provided, and at a point directly above the axis of the roll 11, with a cylindrical recess within which the lower end 14' of a vertically disposed screw 14 20 is positioned. A collar 15, the downwardly and inwardly turned ends of which engage recesses formed in the bearing block, is provided with a central cylindrical aperture through which screw 14 extends, the rod being here reduced in diameter. The lower end portion 14' of the screw has an upwardly directed annular surface which engages the lower surface of member 15 so that this collar serves to transfer the weight of one half of the roll 11 and the entire weight of the 30 associated bearing block to the rod 14.

Immediately above the yoke 15, the rod 14 is provided with threads 16, which threads are in engagement with correspondingly formed threads on the interior of a sleeve member 17 35 which is concentric with and envelops the rod. Sleeve 17 in turn has threads upon its exterior surface which engage correspondingly formed threads in an outer sleeve 18 rigidly secured to the frame or housing in any suitable manner, as 40 for instance by means of bolts 19 and washers 20. If desired, the outer sleeve 18 may be dispensed with and the threads formed on the interior of a cylindrical opening in the horizontal upper cross piece of the housing. It is preferred, however, to employ an outer sleeve, such as 18, not only by reason of the fact that the interior of such a sleeve can be more conveniently threaded and the assembly of the various parts more easily accomplished but also because it can be formed 45 of material more suitable for a threaded member than that used in the fabrication of the frame or housing 10.

The sleeve 17 and screw 14 project vertically upwardly for a considerable distance above the 55 top of the housing 10, and splined upon each is a worm wheel, the worm wheel splined to the outer surface of the sleeve being indicated at 21 and that splined to the screw 14 being indicated at 22. Meshing with the teeth of worm wheel 21 are the 60 teeth of a worm 23 fixed on a shaft 24, and meshing with the teeth of worm wheel 22 are the teeth of a worm 25 fixed on a shaft 26. Obviously rotation of shaft 23 will effect rotation of worm wheel 21 and rotation of sleeve 17, the sleeve 65 being free to rise or fall while rotating by reason of the splined connection between the worm wheel and sleeve surface. In a similar manner, rotation of shaft 26 will cause vertical movement of screw 14.

The rotation of these two shafts 24 and 26 may 70 be brought about by various means, but I prefer to employ electric motors. Thus, a motor is indicated at M which is connected by reduction gearing, including pinion 27 and gear 28, to shaft 75 26, and when this motor M is energized, the

shaft will rotate, thus effecting rotation of the screw 14. The motor is made reversible so the shaft may be rotated in either direction. Shaft 26 extends in both directions from gear 28, and a second worm is mounted on this shaft (illustrated in dotted lines), the teeth of which mesh with those of a worm wheel mounted upon shaft 14' so that screws 14 and 14' are simultaneously revolved upon energization of the motor M.

The sleeve 17 illustrated in Figure 2, and likewise a second and similar sleeve associated with screw 14' (but which is not illustrated) may also be rotated through suitable gearing from the motor N, suitably mounted upon the top of the housing. The shaft 24 is connected to this motor 10 by means of gear 30, pinion 31, and a magnetic clutch 32, and a second shaft 24', similar to shaft 24, is also connected to the motor shaft through gear 33, pinion 34, and magnetic clutch 35, the shafts 24 and 24' being in alignment but not connected with each other otherwise than through the motor. With both magnetic clutches 32 and 35 engaged, therefore, the motor N may be caused to rotate both sleeve 17 and the sleeve associated with the screw 14', the sleeves moving in the same 20 direction of rotation. By disengaging either of the magnetic clutches, either sleeve may be rotated independently of the other and in the desired direction, the motor N being reversible.

In the construction just described, therefore, 30 the motor M may be energized to effect simultaneous rotation of the screws 14 and 14', the sleeves associated with these screws being maintained locked against rotatory movement by reason of the fact that the driving gearings for 35 such sleeves are irreversible. As a result, a quick raising or lowering of the roll 11 occurs. By energizing the motor N with clutches 32 and 35 engaged and maintaining the motor M inactive, the sleeves alone are rotated, and the resulting 40 movement of the roll 11 is slow. Thus, in the event that the pitch of the exterior teeth of the sleeve 17 is 1.5 inches and the pitch of the interior thread is 1.45 inches, the vertical movement 45 of the screw 14 during a single revolution of the sleeve will be only .05 inch or the difference between the pitches of the outer and inner threads of the sleeve. If the sleeve is given only a partial rotation, the travel of the associated screw is, of course, reduced, and by the mechanism just 50 described it is quite possible to raise or lower either screw the desired fraction of an inch, however small, without difficulty, or to give both screws a simultaneous vertical adjustment. A suitable device for indicating either the rotation 55 of the sleeve or the extent of vertical movement of the screws may be utilized if desired.

It will be apparent to one skilled in the art that the design and arrangement of the sleeve and associated parts may be considerably varied 60 without departure from the spirit and scope of the invention.

Having thus described the invention, what is claimed as new and desired to be secured by Letters Patent is:—

1. In a rolling mill, in combination, a frame, a roll mounted in said frame, and mechanism for raising and lowering the roll; said mechanism including a pair of sleeves having threaded engagement with the frame and a pair of screw 70 shafts each having one end operatively connected respectively with one end of the roll, and having threaded engagement with said sleeves, the threaded connections of said sleeves with the frame and screw respectively being of the same 75

hand but differing in pitch, means for rotating said screw shafts and said sleeves, comprising a worm wheel splined to each of said screw shafts and to each of said sleeves, a worm arranged for 5 meshing engagement with each of said worm wheels, a source of power operatively connected to the worms associated with said screw shafts, and means for alternatively or simultaneously connecting a source of power with the two worms 10 associated with said sleeves, whereby fine adjustments of the roll may be effected at either or both ends thereof.

2. In a rolling mill, in combination, a frame, a roll mounted in said frame, a mechanism for 15 raising and lowering the roll, said mechanism including a member having threaded engagement with the frame, a screw having one end operatively connected to the roll and having threaded engagement with said member, the 20 threaded connections of said member with said frame and screw, respectively, being of the same hand but differing in pitch, a worm wheel splined to the screw, a second worm wheel splined to said member, worms meshing with said worm wheels 25 respectively, and a power source connected to each of said worms whereby either may be actuated at the will of the operator.

3. In a rolling mill, in combination, a frame, a roll bearing block slidably mounted in the frame, 30 and means for adjusting the position of said block including a rotatable screw having one end attached to the block in such manner that

the block may be raised or lowered as desired upon rotation of the screw, a rotatable sleeve concentric with and enveloping the screw, said sleeve having threaded engagement interiorly with the screw and exteriorly with the frame, the threads of the sleeve being of the same hand respectively but differing in pitch, and means to independently rotate the screw and sleeve as desired, whereby adjustments of varying degree of fineness may be attained.

4. In a rolling mill, in combination, a frame, a roll bearing block slidably mounted in the frame, a threaded screw having one end attached to the block in such manner that the block may be raised or lowered as desired upon rotation of 15 said screw, means for rotating said screw, said means including an irreversible gearing whereby said screw is locked against rotation when said means is inactive, a sleeve concentric with and enveloping said screw and having threads 20 formed thereon engaging with the threads of the screw, said sleeve also having threads which engage the frame for positively raising and lowering the sleeve upon rotation thereof, and means for rotating said sleeve, said last mentioned 25 means including an irreversible gearing, whereby said block may be raised or lowered by the rotation of either said screw or said sleeve or by simultaneously rotating both screw and sleeve, whereby said roll may be positively positioned 30 and maintained in desired position.
